Filed June 9, 1969, Ser. No. 17,583

Term of patent 14 years

Int. Cl. D12—10

U.S. Cl. D14—3

FIG. 2FIG. 5FIG. 6FIG. 1 is a side elevational view of a camper enclosure for pickup trucks, showing my new design; the broken line showing of a pickup truck is merely for illustrative purposes;

FIG. 2 is a perspective view thereof;

FIG. 3 is a side elevational view thereof; the opposite side, not shown, is a mirror image of the side shown;

FIG. 4 is a rear elevational view thereof;

FIG. 5 is a front elevational view thereof;

FIG. 6 is a top plan view thereof; and

FIG. 7 is a bottom plan view thereof.

I claim:

The ornamental design for a camper enclosure for pickup trucks, substantially as shown and described.
